UNITED STATES PATENT OFFICE.

JOSEPH A. GILLARD, OF MINNEAPOLIS, MINNESOTA.

ACTUATING DEVICE FOR BRIDGING-LEVERS OF SAWMILLS.

SPECIFICATION forming part of Letters Patent No. 747,161, dated December 15, 1903.

Application filed January 19, 1903. Serial No. 139,519. (No model.)

To all whom it may concern:

Be it known that I, JOSEPH A. GILLARD, a citizen of the United States, residing at Minneapolis, in the county of Hennepin and State of Minnesota, have invented certain new and useful Improvements in Actuating Devices for Bridging-Levers of Sawmills; and I do hereby declare the following to be a full, clear, and exact description of the invention, such as will enable others skilled in the art to which it appertains to make and use the same.

My invention relates to sawmills, and is especially directed to improved means for actuating the so-called "bridging-levers" which bridge over the space between the log-deck and the carriage and deliver the logs from the former to the latter over the lumber-conveyer.

The invention consists of the novel devices and combinations of devices hereinafter described, and defined in the claims.

The invention is illustrated in the accompanying drawings, wherein like characters indicate like parts throughout the several views.

Figure 1 is a transverse vertical section taken through a log-deck, log-carriage, and associated parts. Fig. 2 is a similar view to Fig. 1, but shows certain of the parts in different positions; and Fig. 3 is a longitudinal vertical section taken on the line $x^3 x^3$ of Fig. 1.

The numeral 1 indicates the floor-beams, the numeral 2 the log-deck, the numeral 3 one of the rails of the carriage-track, the numeral 4 one of the lumber-conveying rollers, and the numeral 5 the log-carriage of an ordinary sawmill.

The character z indicates logs, one of which in Fig. 2 is indicated by dotted lines.

The character a indicates bridging-levers, of which, as shown, there are two. These bridging-levers a are rigidly secured on a rock-shaft b' , suitably journaled in bearings 45 on the upper delivery portion of the log-deck 2. As shown, the hubs of the bridging-lever a have segmental extensions a^2 , which constitute combined log stops and kickers.

Mounted in suitable bearings b , shown as 50 secured on the floor-timbers 1, is another rock-shaft b' , which is provided with arms b^2 , connected to the respective segments a^2 by con-

necting-rods b^3 . The arms b^2 and connected rods b^3 constitute toggles, as will presently be noted. The rock-shaft b' is further provided, preferably at its intermediate portion, with an arm b^4 , which is connected by a rod b^5 to the piston-rod c of a straight-line reciprocating engine c' , which is preferably actuated by steam in the ordinary way. The said engine c' would be rigidly supported in the ordinary or any suitable way. (Not illustrated.)

As hitherto constructed, bridging-levers similar to those illustrated in the drawings 65 have been actuated by a straight-line reciprocating engine, the piston of which has been so connected to the said bridging-levers that when the latter are thrown down to deliver the logs to the log-carriage the great weight 70 of the logs was sustained only by the pressure of the steam within the cylinder of the engine. Under this pressure of the logs on the bridging-levers under the arrangement just noted the steam is frequently so highly 75 compressed in the upper end of the cylinder of the actuating-engine that the cylinder-head has been blown out and sometimes such cylinder-head has been directly crowded off by having the piston forced against the same. 80

As the principal feature of my invention I so arrange the connections between the bridging-levers and the piston of the engine that when the said levers are thrown down, so as to deliver the logs to the carriage, the 85 weight of the logs will not be sustained or resisted by the engine, but will be taken by parts of the connections. This will become clear by noting the different positions of the parts shown in Figs. 1 and 2. Fig. 1 illustrates the normal positions of the parts, wherein in the bridging arms or levers are thrown upward to hold back the logs from the log-deck. The piston of the engine is then of course thrown downward to its limit and the toggle 95 afforded by the arm b^2 and rod b^3 is buckled. It is also evident that the bridging-levers are thrown pivotally downward, so as to span the space between the log-deck and the carriage and deliver one of the logs from the former 100 to the latter when the piston of the engine is forced upward. In this position of the parts (see Fig. 2) it will now be noted the toggle $b^2 b^3$ stands on a dead-center with the

shaft b' , so that the weight of the log on the bridging-levers is thrown entirely upon the said shaft b' . It is further obvious that in the above-noted position of the parts the weight 5 on the bridging-levers will have no tendency whatever to force further upward the piston of the engine. Hence of course there is no danger of the piston-head being thrown into contact with the upper cylinder-head or that 10 abnormally high pressure will be produced in the cylinder.

From what has been said it will of course be understood that the device above described is capable of considerable modification with 15 in the scope of the invention herein set forth and claimed. However, the actuating connections between the piston of the engine and the bridging-levers, involving a toggle, such as that afforded by the arm b^2 and rod b^3 , and 20 a thrust-shaft, such as that afforded by the shaft b' , constitute the simplest and most efficient device which I have so far been able to devise for the purpose had in view.

What I claim, and desire to secure by Letters Patent of the United States, is as follows:

25 1. In a sawmill, the combination with pivoted bridging-levers and a reciprocating engine, of a connection between the piston of

said engine involving an intermediate thrust-shaft and a toggle, which toggle, when the 30 bridging-levers are thrown down to deliver a log to the log-carriage, stands on a dead-center with respect to said thrust-shaft, thereby throwing the strain from the weight of the log onto said thrust-shaft, substantially as 35 described.

2. In a sawmill, the combination with the log-deck, a carriage and a straight-line reciprocating engine, of a rock-shaft a' mounted on said deck and provided with bridging-levers a and segments a^2 , the thrust-shaft b' mounted in fixed bearings and provided with arms b^2 connected by rods b^3 to the corresponding segments a^2 , said elements $b^2 b^3$ constituting toggles, and the arm b^4 on said shaft 45 b' connected by a rod b^5 to the piston of said engine, which toggles $b^2 b^3$, when the bridge-levers are thrown down, stand on a dead-center with respect to said thrust-shaft b' , substantially as described.

50 In testimony whereof I affix my signature in presence of two witnesses.

JOSEPH A. GILLARD.
